UNITED STATES PATENT OFFICE.

ROBERT JARVIS SMOOTHERS, OF HOLYOKE, MASSACHUSETTS, ASSIGNOR TO JAMES T. ROBINSON, OF HOLYOKE, MASSACHUSETTS.

APPARATUS FOR OFFSET PHOTOGRAVURE PRINTING.

Application filed November 10, 1924. Serial No. 748,971.

This invention relates to an apparatus for offset photogravure printing, and has for its primary object to provide, in a manner as hereinafter set forth, a new and novel means 5 for printing photogravure by offset, in lieu of direct, thereby materially decreasing the cost of operation with respect to the direct method now used, and further for materially increasing the output for a given time without 10 increasing the cost of operation, over that obtained by the present method of direct photogravure printing.

A further object of the invention is to provide, in a manner as hereinafter set 15 forth, a new and novel means for offset photogravure printing, whereby the employment of a solid plate roll or cylinder for direct printing is dispensed with, thus reducing the cost of operation.

20 A further object of the invention is to provide, in a manner as hereinafter set forth, a new and novel means for offset photogravure printing whereby the drying step, after the work leaves the press, now 25 employed in the present method of direct photogravure printing is dispensed with as the work dries as it leaves the impression cylinder, owing to the offset method of printing.

30 A further object of the invention is to provide, in a manner as hereinafter set forth, a new and novel means for offset photogravure printing, whereby a removable bendable plate having the design thereon 35 provided with pits or wells, such plate termed an "intaglio" plate, is detachably secured to a plate roll and acts in conjunction with a transfer roll arranged thereover for printing, by offset, photogravure upon a web travelling against an impression cylinder or roll superposed with respect to the transfer roll or cylinder, thereby overcoming direct printing from a solid roll and expediting the work, as well as reducing operating costs, 40 more particularly with respect to the great reduction in cost of the plate carrying the design, which is ultimately printed upon the web.

With the foregoing and other objects in 50 view, the invention consists of the new and novel means for offset photogravure printing as hereinafter more specifically described and illustrated in the accompanying drawings, wherein is shown a form of apparatus 55 capable of carrying the method into effect,

but it is to be understood that changes, variations and modifications can be had which will fall within the scope of the claim hereunto appended.

In the drawings wherein like reference characters denote corresponding parts throughout the several views:—

Figure 1 is a diagrammatic view of an apparatus for offset photogravure printing, in accordance with this invention.

Figure 2 is a diagrammatical view of an apparatus for offset photogravure continuous color printing in accordance with this invention.

Figure 3 is an edge view, broken away, of 70 the intaglio plate employed.

Figure 4 is a fragmentary view, in section, of the plate, illustrating the pits or wells.

Figure 5 is a fragmentary view, in section, 75 of a plate or transfer cylinder in open position.

Figure 6 is a like view of the transfer or plate cylinder in closed position.

Referring to Figure 1 of the drawings, 1 80 denotes a plate cylinder or roll provided with a substantially seamless, removable plate 2, having the design thereon provided throughout with pits or wells and said plate is termed an intaglio plate. Arranged 85 below the cylinder or roll 2 is an ink supply element 3 having operating therein an inking roll 4, which is employed for supplying the ink to the plate 2, so that the pits or wells will take up or be filled with the ink. 90 Arranged in cooperative relation with respect to the plate 2 is an ink scraper element 5, against which the plate 2 rides. The function of the element 5 is to remove the surplus ink from the plate 2 and which will 95 be discharged into the ink supply element 3. Arranged in superposed relation with respect to and of the same diameter as the diameter of the cylinder or roll 1, is a transfer or blanket cylinder or roll 6, provided with a substantially seamless blanket 100 7 employed for transferring the design, in ink, to the web 8, which travels between the top of the cylinder or roll 6 and the bottom of an impression cylinder or roll 9.

105 Referring to Figure 2 of the drawings, there is illustrated a means for offset photogravure continuous three color printing, although it is to be understood that the means can be arranged to apply a greater or less 110

number of colors, as the illustration of three colors is by way of example. By reference to Figure 2, 10, 11 and 12 indicate plate cylinders or rolls provided respectively with 5 substantially seamless intaglio plates 13, 14 and 15. Arranged in superposed relation with respect to the cylinders or rolls 10, 11 and 12 are respectively the transfer cylinders or rolls 16, 17 and 18 provided respectively 10 with substantially seamless blankets 19, 20 and 21. Common to the cylinders or rolls 16, 17 and 18 is an impression cylinder 22, between which and the blanket rolls 16, 17 and 18 the web or sheet 23 travels. The 15 plate 13 has a portion of the design for one color, plate 14 another portion of the design for a different color, and the plate 15 the remaining portion of the design for another color, that is to say the portion of the design 20 on the plate 13 will be printed by the offset method in one color on the web 23, and when the web reaches the blanket 20 another portion of the design will be printed, by offset, in a different color on the web 23, and when 25 the latter reaches the blanket 21 the design will be completed by offset printing but the completed portion of the design will be of a different color and by the foregoing arrangement offset photogravure color printing from a continuous standpoint is had.

Associated with each of the rolls 10, 11 and 12 is an ink supply element 3 and an inking roll 4.

The plate, which is removably secured to 35 the plate cylinder or roll is formed from a thin metallic sheet 24, capable of being bent to surround the plate cylinder or roll. Opposed edges of the sheet 24 are bevelled in parallel planes, as at 25, 26, so that the plate 40 when detachably secured to its cylinder or roll will have the bevelled edges thereof overlapped, under such conditions forming a substantially seamless cylindrical plate. The design on the plate is provided through- 45 out with pits or wells 27, see Figure 4, and the plate after completion is what may be termed an intaglio plate.

The blanket which is removably secured to the transfer cylinder or roll also has a 50 pair of opposed edges bevelled in the same manner as sheet 24, so that when the blanket is mounted in position the bevelled edges will overlap, as indicated at 28 in Figures 1 and 2, thereby providing what may be 55 termed a substantially seamless cylindrical blanket when the latter is mounted in position on the transfer cylinder or roll. The plate cylinder or roll, or the transfer cylinder or roll is constructed in the manner as 60 disclosed in Figures 5 and 6 of the drawings, and by reference thereto 29 indicates the intaglio plate or the transfer blanket. The construction of cylinder or roll as illustrated in Figures 5 and 6, is similar to that set 65 forth in my application filed April 2, 1924,

Serial Number 703,775. By reference to Figures 5 and 6, the body portion of the cylinder or roll comprises a fixed section 30 formed with an enlarged opening 31, having one side edge squared, as at 32, and its other side edge inwardly bevelled, as at 33. The body portion of the roll further includes a segment-shaped section 34 having one side terminal bevelled, as at 35, which abuts against the bevelled edge 33. The section 34 is pivoted and has connected therewith one of the removable sections 36 of the body portion. The section 30 has connected therewith the other removable section 37 of the body portion. The sections 36 and 37 are 80 bevelled and the bevels of said sections form continuations of the bevelled edges of the plate or blanket 29. The sections 36 and 37 are secured against the inner face of the plate or blankets 29. The section 34 is 85 adapted to be clamped in position by the element 38 and when clamped the sections 36 and 37 will assume the position shown in Figure 6, whereby the bevelled edges of the plate or blanket 29 will overlap and when 90 said plate or blanket 29 is secured in the position shown in Figure 6, it then will be in cylindrical form and substantially seam- less.

As is well-known in photogravure printing, a solid plate roll is employed for direct printing and which is unusually expensive to produce, that is to say when the design is formed on a cylinder or roll. These solid rolls are bodily removed from the press as well as positioned bodily with respect to the impression roll. Sometimes it is necessary to dismantle certain portions of the press. It is also inconvenient to remove and replace the plate roll when occasion requires. The 100 employment of the intaglio plate, in accordance with this invention does not require the plate cylinder or roll to be removed from the press, as the plate or the blanket can be conveniently removed and replaced when 105 occasion requires without dismantling the press in any manner or removing the plate cylinder or roll or the blanket cylinder or roll.

The apparatus for offset photogravure 115 printing, in accordance with this invention, overcomes the necessity of drying the work after printing. Then furthermore by printing photogravure by offset, the output is 120 materially greater, in a given time, than by the direct method, and it is thought that the many advantages of an apparatus for offset printing photogravure, in accordance with this invention can be readily understood, and although the preferred embodiment of 125 the invention is as described, yet it is to be understood that changes therein can be had which will fall within the scope of the invention as claimed.

What I claim is:—

An apparatus for offset photogravure printing comprising a revoluble plate carrying cylinder, a split cylindrical printing plate formed with an impression surface having a pitted or welled design, said plate detachably secured to and completely enveloping said cylinder and having its opposed edges beveled, overlapping and abutting throughout to form a substantially seamless impression surface, a revoluble blanket carrying roll arranged over said impression surface, a split cylindrical blanket detachably secured to and completely enveloping said roll, said blanket having its opposed edges beveled, abutting throughout and overlapping to provide a substantially seamless transfer surface for transferring from said impression surface the design from the latter in ink for application to the lower face of a web or sheet traveling over said blanket, an impression cylinder arranged over said transfer surface and co-acting with said blanket roll to impress the transferred design on said web or sheet, means positioned in cooperative relation with respect to the plate carrying cylinder for applying ink to the design on said impression surface, and means acting to remove surplus ink from said pitted or welled design prior to the taking up of the design in ink by said transfer surface.

In testimony whereof, I affix my signature hereto.

ROBERT JARVIS SMOTHERS.
